UNITED STATES PATENT OFFICE

ERNEST YEOMAN ROBINSON, OF WITHTINGTON, MANCHESTER, ENGLAND, ASSIGNOR
TO METROPOLITAN-VICKERS ELECTRICAL COMPANY LIMITED, A COMPANY OR-
GANIZED UNDER LAWS OF GREAT BRITAIN

VACUUM ELECTRIC TUBE

Application filed June 27, 1924, Serial No. 722,811, and in Great Britain July 16, 1923.

This invention relates to vacuum electric tubes and in particular to methods of supporting the electrodes in such tubes.

The object of the invention is to provide 5 an improved construction whereby the electrodes of vacuum electric tubes may be assembled before they are inserted into the container so that small gaps between the electrodes may readily be provided if desired. 10 According to the invention all the electrodes are mounted on a framework which entirely supports them, said framework being connected to and supported by the container. The supporting framework may consist of insulating material such as glass which 15 preferably has a high melting point for example, pyrex glass, but in the preferred form it consists in part of metal and in part of insulating material. The said supporting 20 framework is mounted on or supported by the container preferably by means of metallic attachments.

In one form the said framework is supported by metal clips from a re-entrant stem 25 which may be the re-entrant tube which carries the leading-in wires to the device, or otherwise attached thereto.

Furthermore, in the preferred method the major members of the frame and electrodes 30 are parallel and are supported in the following manner. Metallic cross-pieces fit on the members or stems and are provided with holes, recesses, projections or other suitable means for registering and holding the electrodes which they support. Cross pieces are 35 arranged to fit into or on to the members or stems so that no adjustment is required in assembling the electrodes. By this means the electrodes are constrained in the direction of 40 their length. Furthermore, in accordance with this preferred modification of the invention means are provided that while the electrodes are constrained in the direction of their length, the electrodes are able to expand or contract in this direction. For this 45 purpose one or more of the supporting cross pieces may be flexible or elastic or the electrodes may be slidably mounted in one or more of the registering cross pieces or one 50 or more of the cross pieces may be slidably

mounted on the supporting framework. If desired the electrodes may be held in tension.

To enable the invention to be clearly understood it will now be described with reference to the accompanying drawings in which Fig. 1 is an elevation of a vacuum electric tube having the electrodes supported on the framework in accordance with the invention, and Figs. 2 and 3 are plan views of details. 55 Figs. 4 and 5 are detail perspective views of electrode supporting cross members of channel section employed in the construction shown in Figure 1. Figs. 6, 7 and 8 are respectively, a transverse section and front and side elevations of a further electrode structure comprising two distinct supporting frameworks and Figs. 8^a to 12 inclusive are views of details thereof. Fig. 13 represents a vertical section of a vacuum electric tube 60 embodying an electrode-supporting framework constituted as shown in Figs. 7 to 12. Figs. 14 and 15 are respectively front and side elevations of a still further electrode 65 structure, and Figs. 16 to 22 are views of details thereof.

Similar reference numerals are used where possible in the several figures of the drawings.

Referring first to Figs. 1, 2 and 3 the evacuated envelope 1 has within it an electrode assembly comprising two parallel cathode filaments 2 and an anode 3. The anode and cathode are mounted upon a rectangular framework 4 comprising a pair of parallel side members 5 of insulating material such as glass or steatite. The insulating side members 5 are connected together at their upper ends by means of a metallic end member 6 of nickel for example which is formed of sheet material and comprises a transverse portion 7 carrying two socket portions 8 into which the upper ends of the insulating members 5 are fitted. The member 6 is connected to the members 5, by means of the binding wire indicated at 9. The transverse portion 7 contains a central socket 10 the axis of which is parallel with the sockets 8. The central socket 10 contains a hook or loop 11 to which is attached a spring 12 by which the filament cathode 2 is placed 75 80 85 90 95 100

in tension as will be hereinafter described. The central socket 10 is preferably provided with a window 13 to permit inspection of the hook 11 and spring 12.

- 5 The insulating members 5 are connected together at their lower ends by means of a metallic clamping member 14 of nickel for example which is secured to the members 5 by means of the binding wire indicated at 15.
- 10 The member 14 is adapted to be clamped in any suitable manner to the re-entrant tube 16 which is sealed at 17 to the lower end of the envelope 1. The re-entrant tube 16 is provided at its upper end with a pinch or seal 18 through which pass the leading-in wires 19 to the filament as will be well understood by those skilled in the art. The members 5, 7 and 14 thus constitute a rigid rectangular framework upon which the anode and cathode 20 are supported in such a manner that they are registered with respect to one another as will be now described.

The lower ends of the cathode filaments 2 are connected respectively to supporting cross members 20 and 21 which comprise sheet metal of relatively thick gauge and are provided with eyes 22 at their ends into which the side members 5 are fitted. The members 20 and 21 are separated from one another by 25 insulating washers 23 of glass or steatite for example and are prevented from moving in an upward direction along the side members 5 by means of enlargements 24 provided on the latter. Said members 20 and 21 may be 30 secured on the side members 5 and prevented from sliding towards the end 14 by binding wire (not shown) or otherwise but this is not necessary since they are pulled up against the stop 24 by the filaments. The cathode filaments 2 and the lead-in wires 19 are respectively welded to the members 20 and 21. The other ends of the cathode filaments 2 are attached to a cross piece 25 which is provided with a hook or loop 26 which in turn 35 is engaged by the spring 12 for maintaining the filaments in tension. By the arrangement described the two filaments 2 and the rectangular supporting framework are maintained in one plane.

- 40 The filaments 2 pass through perforations in a cross piece 27 which thus serves effectively to register the cathode with respect to the rectangular framework. The cross member 27 which is conveniently of sheet metal of nickel or molybdenum for example 45 bent to a channel section as shown in Fig. 4 is provided at its ends with perforations through which the side members 5 pass. The member 27 is secured upon the members 5 in 50 contact with the end member 6 by the binding wire 9. When the tube is of the type described in my Patent No. 1,677,850, granted July 17, 1928, the short-circuiting cross piece 28 welded to the filaments 2 maintains the 55 upper ends thereof cool so that the discharge

is confined to inter-electrode gaps: the filaments at the other ends are maintained cool by means of the members 20 and 21.

The anode 3 comprises a pair of similar superposed plates 29 of molybdenum or nickel for example (see especially Fig. 2) each of which is provided with two parallel semi-cylindrical channels 30 so disposed that when the plates 29 are placed together two cylindrical tunnels are provided through which the filament 2 passes. The two plates 29 may be connected together by means of staples 31, by welding or otherwise. The anode thus constituted is so located within the rectangular framework that it lies in the plane of the latter. It is secured to said rectangular framework by means of a group or plurality of cross pieces 32 and 32', three of which are shown in Fig. 1 and one of which is shown in plan in Fig. 3. Each cross piece 32 or 32' is formed of sheet metal and is provided at its ends with perforations 34 through which the side members 5 of the framework pass. Each plate is also centrally provided with a slot 35 comprising a rectangular portion and two circular portions so that its shape is similar to the external contour of the anode the slot being wider than the flat portions of the anode so that the anode is registered by the tunnels therein as will be readily understood by reference to Figs. 2 and 3. One of these cross pieces, for instance the upper one 32, is preferably formed as illustrated of channel section as shown in Fig. 5 to provide rigidity. The remaining cross pieces 32' are preferably flexible to permit expansion of the anode. The arrangement, however, is such that the anode is always constrained with reference to the framework and consequently also with reference to the cathode except in a longitudinal direction. In this manner the tensioned filament is prevented from touching the anode whereby the inter-electrode gap may be made short. The anode is secured to one of the cross pieces, for example to the upper cross piece 32, by welding or by the provision of one or more tongues on one of these members adapted to engage the other member. The cross pieces are secured in position upon the side members 5 by means for example of the binding wire indicated at 36. It will be noted that the cross pieces 32 and 32' provide additional strength and rigidity to the rectangular framework.

The anode is connected to the rigid cross piece which in turn is connected to a lead-in wire 37 which passes through a seal 38 in the upper end of the envelope 1. Alternatively the lead-in wire may pass through the seal 18 of the re-entrant tube 16, the arrangement illustrated being preferred.

With the construction described the electrodes are positively registered with respect to one another and to the rigid framework as previously mentioned. In particular the

peculiar construction of the filament supporting members 20 and 21 prevents the filaments from moving during evacuation of the envelope or during the life of the valve. Furthermore said supports are adjustable in a direction at right angles to the plane of the framework so that the lower ends of the filaments may be welded to the supports whilst held in a jig said filaments being subsequently 10 adjusted, if necessary, in a direction at right angles to the plane of the framework by bending the supports. It will be noted that the filaments are parallel with one another and with the sides of the framework which 15 construction permits the inter-electrode gap being made very small without any liability for the filaments touching the anode. It also permits the parts of the electrodes being formed of pressings and stampings and at 20 the same time enables the necessary hand adjustment to be considerably reduced.

Referring now to Figs. 7 to 12 inclusive the support or framework upon which the electrodes are mounted comprises a main frame 25 having two side members 65 which consist of nickel or steel tubes into the four open ends of which are inserted steatite or glass rods 66, and an auxiliary frame embodying parallel side members or rods 73 and other parts supported 30 on the main frame as hereinafter described. The portions of the rods 66 of the main frame external to the tubes 65 are of greater diameter than the portions 67 located within the tubes 65. The portions 67 make screw-threaded engagement with the tubes 65 or the latter may be split and clamped upon the portions 67. The main frame is completed by nickel end-members 68 and 69 the side portions of which embrace the ends of the steatite or 35 glass members 66 and are secured thereon by wire binding 70. The end portions of the members 66 are of smaller diameter than the central portions thereof.

The anode 23 is supported from the side 45 tubes 65 of the main frame by means of a group or plurality of cross pieces 71 and 71' one of which, namely the lowest one 71, is rigid, being for example of channel section as shown in Fig. 8^a. The members 71, 71' 50 may be secured to the tube 65 by means of binding wire as indicated at 72. It will thus be seen that the anode is in electrical connection with the side members 65 of the main frame. The cathode filament is supported 55 from the steatite members 66 by means of the independent auxiliary frame which comprises four parallel molybdenum rods 73 which are attached to one another in pairs by means of cross members 74 welded thereto. 60 The two pairs of rods 73 are disposed on either side of the anode as clearly shown in the side view, Fig. 8. The rods are supported upon the main frame previously described by means of cross pieces 75, 76, 77 and 78. One 65 of such members is shown in plan in Fig. 9.

It has two end perforations 79 through which the members 66 pass and four perforations 80 into which the frame rods 73 are secured. Whilst the end cross pieces 75 and 78 are as illustrated in Fig. 9 the intermediate cross pieces are provided with central clearance holes to permit other members of the structure to pass therethrough. Two parallel cathode filaments are employed connected by the short-circuiting strip 28^a at one end 70 whilst the other ends of the filaments are secured to relatively thick nickel wires or rods 81 the ends of which are drilled (as clearly shown in section in Fig. 8) to accommodate the ends of the filaments which are welded therein. The nickel wires 81 pass through respective insulating bushes of steatite, glass or mica 82 which are gripped in the nickel end piece 69, steatite, glass or mica washers 83 being also provided at the ends of the bushes 82. The wires 81 are secured within the bushes 82 by welding a small piece of nickel 84 on to the said wires on either side of the bushes. The wires 81 are registered in position by means of two crosspieces which are mounted upon the filament supporting auxiliary frame. One of such cross pieces is shown in plan in Fig. 10. It comprises a substantially rectangular plate 85 having 80 perforations provided with steatite bushes 86 through which the members 73 of the filament supporting frame pass, and a perforation through which the wire 81 passes. The bushes are secured in position upon the rods 73 by pieces of nickel welded thereon.

The constraining means at the other end of the cathode filaments consists of a substantially H-shaped nickel plate 87 illustrated in plan in Fig. 11. The plate 87 is provided with four perforations through which the rods 73 pass for supporting the plate on the latter. Attached to the cross member of the plate 87 is a molybdenum wire 88 having hooks or eyes 89 through which the filament wires pass. The cathode filaments are tensioned by means of a pair of springs 90 which are attached at one end to two tabs 91 provided on the cross strip 28^a which should be of a flexible construction and to the frame member 68 at the other end.

The filaments are registered at points intermediate of their length by means of tungsten hooks or eyes 92 provided on wires 93 which are pinched into glass beads 94. Additional molybdenum wires 95 (see especially Fig. 12) are also pinched into the glass beads 94 and are welded to the filament supporting frame members 73. The wires 93 pass through shields 96 inserted over but spaced away from the holes provided in the wall of the anode structure, as shown in Fig. 8. When the space current of the device is led into the filament at a plurality of points the wires 93 of the constraining loops 92 are brought out to the exterior of the tube and 100

the short-circuiting strip 30 is attached to the frame member 68 by means of flexible conductor 97.

With the construction above described it will be appreciated that the filament is registered at a number of points along its length and at the same time a long leakage path is obtainable between the filament supports and the anode supports. The complete electrode structure may be assembled in an envelope in the manner now to be described with reference to Fig. 13 wherein for simplicity only the main members of the structure are illustrated.

The envelope is indicated at 98 and comprises as shown a relatively large central portion merging into two substantially cylindrical end portions of smaller diameter. The electrode structure is supported within the smaller end portions of the envelope 98 by means of two resilient rings 99 attached to the extremities of the main framework. Re-entrant tubes 100 are provided at the ends of the envelope. The five tapping points to the filament, that is to say the four wires 93 and a conductor connected with the upper frame member 68, pass through a seal on the upper re-entrant tube whilst the two filament leads connected with the wires 81 pass through a seal on the lower re-entrant tube. The lead-in wire 101 for the anode passes through a separate seal 102 in the envelope 98. The framework is flexibly attached to the upper re-entrant tube 100 by means of a clip 103 connected with the frame by members 104. The connection to the clamp 103 is merely flexible and has only sufficient rigidity to restrain the framework in a lateral direction, motion in other directions being prevented by the resilient rings 99. This arrangement enables the electrode structure to be readily assembled in the envelope and rigidly holds it against movement in an axial direction.

When the device illustrated in Figs. 7 to 13 inclusive is of the three-electrode type the grid is advantageously supported by the cathode supporting framework.

In the electrode structure illustrated in Figs. 14 and 15 the supporting framework comprises four parallel rods of insulating material such as glass or steatite, namely the two rods 144 and the two rods 145 which are in a plane at right angles to the rods 144. The rods are supported in metallic end members 146 and 147. The end member 146 which is shown in plan in Fig. 16 comprises a cross shaped member having four arms 148 at right angles to one another, each having at its extremity a socket 149 for the end of an insulating rod. The sockets 149 may be clamped upon the ends of the rods 144 and 145 by means of the binding wire indicated at 150 or by other means. The lower member 147 which is illustrated in plan in Fig. 17 is similar to the member 146 illustrated in Fig. 16 ex-

cept that it is provided with a pair of additional sockets 151 the purpose of which will be hereinafter explained.

The anode and filament are of the type described in Figs. 1 and 2. The anode in the example illustrated comprises two portions 152 and 153 which are in alignment with one another and overlap one another as indicated at 154 and are connected electrically in parallel. The two anode portions 152 and 153 are secured together by means of the staples 31 which are employed for connecting together the plates of which the anode is formed as described in connection with Figs. 1 and 2. The anode is supported from the insulating frame members 144 by a group or plurality of cross pieces 32 and 32' the lowermost cross piece 32 being of channel section as shown in Fig. 22 to provide rigidity and to which the anode is secured, for instance by means of the tags 155.

The cathode is mounted in the manner described in my Patent No. 1,720,442 granted July 9, 1929.

The two filaments 2 are attached at their lower ends to two nickel rods 156 which are mounted in alignment with the filaments and the upper ends of which are drilled to receive the ends of the filaments which are welded therein. The nickel rods 156 are supported by the lower frame member 147 and pass through insulating bushings of steatite, glass or the like 157 which are clamped within the clamps 151 of said lower member. The upper ends of the nickel rods 156 are registered with respect to the framework by means of respective cross members 158 one of which is shown in plan in Fig. 18. Each cross member 158 is provided with end perforations 159 by means of which it is mounted upon the insulating frame members 145 and with a laterally displaced central perforation 160 through which a nickel member 156 passes. The two cross pieces 158 are spaced apart by means of an insulating washer 161. The cross pieces 158 are secured upon the rods 145 by means of rectangular sheet metal members 163 having perforations 164 by means of which they can be threaded upon the rods 145 whereon they are secured by means of binding wire as shown.

One of such members is shown separately in perspective in Fig. 19.

The upper ends of the filaments are provided with tabs 165 to which are attached tensioning springs 12 which are in turn attached to hooks connected to the frame member 146. The ends of the filaments are short-circuited by means of the flexible strip 28 and the filaments are registered by means of a cross strip 166 which is illustrated in plan in Fig. 20. Said strip is supported upon the frame members 145 and has welded to it a transverse wire 167 of molybdenum or tungsten for example having at its ends eyes 168 through which the filaments pass. The filaments are

constrained intermediately of their extremities by means of two cross pieces 169 supported upon the frame members 145. One of such cross pieces is illustrated in perspective in Fig. 21. It comprises a strip 170 perforated at its ends, and perforated auxiliary portions 171, as clearly shown. Each strip 170 passes through a slot out in the central portion of the anode plates between the tunnels thereof. Each strip 170 is provided with a transverse wire 172 preferably of tungsten having an eye 173 at the end through which the filament passes, each slot in the anode extending into a tunnel. The members 169 are mounted upon the frame members 145 and the auxiliary portions 171 are provided so that the members 169 may be bound to the rods 145 with only a small separation between them. In the case of valves constructed in accordance with my Patent No. 1,677,850 hereinbefore referred to if the opening into the anode tunnels is comparatively small the space current will not escape therethrough owing to the fact that the parts of the cathode which are adjacent the openings will be maintained cool by reason of the eyes 173 on the members 169. If necessary however the discharge may be prevented from passing through the perforations by means of shields mounted upon the cross pieces 169 which are of course in electrical connection with the portion of the filament which is to be shielded.

The main supporting framework may be mounted within the valve envelope in any desired manner. It is conveniently mounted therein by means of the rings 99 as described in connection with Figs. 7, 8 and 13.

It will be understood that various modifications may be made in the construction of the framework and the mounting of the electrodes thereon without departing from the scope of the invention.

I claim as my invention:—

1. For a vacuum space current device, an electrode structure comprising a rigid elongated support, a plurality of electrode carriers having portions engaging said support and constrained to move only in a direction longitudinally thereof to aline said carriers longitudinally and position them transversely of said support, said carriers having electrode-positioning surfaces which are alined when said carriers are alined on the support, and an elongated electrode, which is rectilinear and of uniform cross section throughout its length, said electrode engaging the alined electrode-positioning surfaces of said carriers and being thereby positioned transversely with respect to said support.

2. For a vacuum space current device, an electrode structure comprising a rigid framework at least in part of insulating material with a plurality of parallel side members, an electrode, and a plurality of cross members

having portions shaped to slidably embrace said parallel side members and thereby aline the cross members longitudinally of the framework, said cross members having electrode positioning portions which are alined when said cross members are alined on the framework, and correspond in shape with and engage the electrode to position the latter parallel with the side members of said framework.

3. For a vacuum space current device, an electrode structure comprising a rigid framework at least in part of insulating material with a plurality of parallel side members, an electrode, and a plurality of parallel cross members having eyes through which said side members pass slidably to aline the cross members longitudinally of the framework, said cross members having electrode-engaging portions which correspond with the shape of the electrode and are alined, when the cross members are alined on the framework, to position the electrode parallel with the side members of said framework.

4. For a vacuum space current device, an electrode structure comprising a rigid framework at least in part of insulating material with a plurality of parallel side members which throughout at least a part of their length are of uniform cross section, an electrode, and a plurality of parallel cross members having a plurality of surfaces which respectively embrace slidably said side members and thereby aline the cross members longitudinally of the framework, said cross members having electrode-engaging portions which correspond in shape with the cross section of the electrode which they engage and which portions are alined, when the cross members are alined, to position the electrode with respect to said framework and to constrain the electrode to move only in a direction longitudinally of the framework.

5. For a vacuum space current device, an electrode structure comprising a support embodying a rigid framework at least in part of insulating material with a plurality of parallel side members, an anode, and a plurality of parallel cross members having eyes shaped and located to slide longitudinally on said parallel side members to aline said cross members longitudinally on the framework, said cross members having other eyes of predetermined shape and location which are alined, when the cross members are alined on the framework, and embrace the anode at different points in its length and thereby support and position the anode in the framework and constrain it to move only in a direction longitudinally of the framework.

6. For a vacuum space current device, an electrode structure comprising a support, electrodes having parts co-axially arranged, a group of electrode supporting members for one of said electrodes having portions which

slidably engage said support longitudinally and thereby aline said members longitudinally thereon, said members having electrode-positioning portions of predetermined location thereon which are alined when said members are alined with respect to said support, and supporting means for another of said electrodes including an additional electrode supporting member having a portion which slidably engages said support longitudinally and also having an electrode positioning portion of predetermined location thereon which is alined with the electrode positioning portion of said group of supporting members when 15 said additional supporting member is alined with respect to said support, the electrode-positioning portions of at least two of said group of supporting members engaging one of said electrodes at different points in its length, and the electrode-positioning portion of said additional member engaging another of said electrodes at a point between its ends and thereby positioning said electrodes with parts thereof arranged co-axially and constraining them to move only in the direction 20 of their axis.

7. For a vacuum space current device, an electrode structure comprising a rigid framework at least in part of insulating material 30 with a plurality of parallel side members, an electrode, a plurality of parallel cross members having portions which are slidable longitudinally on to said parallel side members to aline said cross members longitudinally thereon, said cross members having electrode-positioning portions of predetermined shape and location which are alined when said cross members are alined, and engage the electrode at different points in its length 35 and thereby position the electrode transversely with respect to the framework, and means for preventing longitudinal movement of said electrode as a whole with respect to said parallel side members.

8. For a vacuum space current device, an electrode structure comprising a framework at least in part of insulating material and embodying a main rigid frame and an auxiliary frame supported by the main frame, 50 said frames having parallel side members, a plurality of electrodes, a group of parallel cross members for supporting one of said electrodes having portions engaging the parallel side members of the main frame to aline said group of cross members on the main frame, said group of cross members having electrode-positioning portions of predetermined location thereon to engage its respective electrode at different points in its length and 55 supporting means for another of said electrodes including a cross member having portions engaging the parallel side members of the auxiliary frame and also having an electrode-positioning portion of predetermined 60 location thereon and engaging its respective

electrode, said cross members thereby positioning the electrodes transversely with respect to one another.

9. For a vacuum space current device, an electrode structure comprising a rigid framework at least in part of insulating material and consisting of end members and parallel side members, a group of parallel cross members having portions which slidably embrace parallel side members of the framework and thereby aline said cross members longitudinally of the framework, said cross members having positioning portions for one electrode which are in common alinement when the cross members are alined, an additional cross member having portions slidably embracing side members of the framework and also having an electrode-positioning portion, a filament cathode connected at one end with one end member of the framework and means supported on the framework and connected to and supporting the other end of the cathode, said filament cathode being engaged between its ends by the electrode-positioning portion of said additional cross member, and an anode engaged at different points in its length by the electrode-positioning portions of said group of cross members, said cathode and anode being thereby spaced with respect to one another.

10. For a vacuum space current device, an electrode structure comprising a rigid framework at least in part of insulating material with a plurality of parallel side members, a plurality of parallel cross members having portions which embrace said parallel side members and thereby aline said cross members on said framework, said cross members having electrode-positioning portions thereon which are alined when said cross members are alined on the framework, certain of said cross members being rigidly fixed to said parallel side members, at least one electrode positioned at intervals in its length on said cross members by sliding engagement with the electrode-positioning portions thereof, said electrode being fixed to at least one of said fixed cross members.

11. For a vacuum space current device, an electrode structure comprising a rigid framework composed in part of insulating material and in part of metal and having longitudinal members, a plurality of cooperating electrodes, a group of cross members for supporting one of said electrodes having portions which engage longitudinal members of the framework and thereby aline said cross members longitudinally thereon, supporting means for another of said electrodes including an additional cross member having portions which engage longitudinal members of the framework, said group of cross members being insulated from said additional cross member by said insulating material of the framework, said group of cross members

having electrode-positioning portions in pre-determined position thereon which are alined when said cross members are alined on said framework and which engage and position the respective electrode and said additional cross member having an electrode-positioning portion in predetermined position thereon which engages and positions its respective electrode.
